DESIGN FOR A HAT OR SIMILAR ARTICLE

Ruth Deutsch, New York, N. Y.

Application October 14, 1944, Serial No. 115,779

Term of patent 3½ years

(Cl. D3—13)

To all whom it may concern:

Be it known that I, Ruth Deutsch, a citizen of the United States of America, residing in New York city, county of New York, and State of New York, have invented a new, original, and ornamental Design for a Hat or Similar Article, of which the following is a specification, reference being had to the accompanying drawing, forming part thereof, wherein,

Figure 1 is a side perspective view of a hat or similar article showing my new design;

I claim:

The ornamental design for a hat or similar article, substantially as shown and described.

RUTH DEUTSCH.
